UNITED STATES PATENT OFFICE.

JOSEF PEJCHAR, OF BROOKLYN, NEW YORK.

JEWELRY SETTING AND THE LIKE.

Application filed March 24, 1920. Serial No. 368,409.

To all whom it may concern:

Be it known that I, JOSEF PEJCHAR, a citizen of the United States, and resident of the borough of Brooklyn, county of Kings, city and State of New York, have invented 5 certain new and useful Improvements in Jewelry Settings and the like, of which the following is a specification.

My invention relates to an article made of 10 sheet metal and designed primarily for use as a so-called jewelry setting box, that is, a jewel setting or holder of box-like character, although it is available for other purposes, as indicated below. The object of my present 15 invention is to provide a simple and very strong article of the character mentioned, the manufacture of which may be conducted readily by artisans who do not have machinery and apparatus by which such articles 20 may be produced in a complete state, and besides, the improved article may be readily made of relatively small dimensions for which certain ordinary processes of manufacture, such as casting, are not available. 25 Several examples of my present invention are illustrated by the accompanying drawings, in which Fig. 1 is a plan view showing one form of my improvement; Fig. 2 is a cross section thereof on the line 2—2 of Fig. 30 1; Figs. 3 and 4 are cross sections of two other forms of my invention; Fig. 5 is a plan view of another form of my invention, and Fig. 6 is a cross section thereof on the line 6—6 of Fig. 5; Fig. 7 is a plan view of still 35 another form of the invention; Fig. 8 is a longitudinal section thereof, on the line 8—8 of Fig. 7; Fig. 9 is a cross section on the line 9—9 of Fig. 8; Fig. 10 is a plan view and Fig. 11 a side view of a further form; and 40 Figs. 12 and 13 are views corresponding respectively to Figs. 10 and 11 and showing another construction of similar character.

As shown in Figs. 1 and 2, a piece of suitable sheet metal is bent to form a structure 45 approximately H-shaped in cross section, with two parallel vertical side members 20 of full height, connected at the bottom by bends with two shorter vertical members 21 lying close to the lower portions of the respective side members 20, the upper ends of 50 said members 21 being connected by bends to a horizontal cross member 22. Preferably, as shown, the height of the members 21 is about one-half the height of the members 20, 55 so as to bring the cross member 22 half-way between the top and the bottom of the struc-

ture; the cross member may however be located at different distances from the top and the bottom, by making the height of the members 21 more or less than half the height 60 of the side members 20. If desired, the members 21 may be connected rigidly with the members 20 (as by soldering their adjoining parallel surfaces), but this is not necessary, and the device may be used exactly as 65 shown, said adjoining parallel surfaces being in contact with each other, although for the sake of clearer illustration a separate line has been used to indicate each of said surfaces. 70

The structure described above forms a holder that may be used as a so-called jewelry setting box, to receive jewels or other ornaments, such as indicated at A near one end of Fig. 1, the free ends of the upright members 75 20 being pressed into holding engagement with the jewels in the usual way, by means of a file or like tool, while each of the members 21 forms a backing for the lower portion of the corresponding side member 20. It will 80 be seen that the side members 20 have no backing above the cross member 22 (which forms the bottom of the holder or jewelry setting box) and are therefore more easily forced inward than the portions below the 85 cross member, which portions, being backed by the upright return members 21, are more rigid than the upper portions of the side members 20. The side members therefore 90 have considerable elasticity, at least at their upper portions, and when the connections between the side members 20 and the return members 21 are made exclusively by the bends at their lower edges, each side member, 95 from such bend upward, can spring, within certain limits, toward and away from, the companion return member. The upper edges of the members 20 will therefore grasp the stone or other jewelry article firmly, and a 100 very reliable holder is thus obtained.

It will be obvious that the device described above may be used for purposes other than holding jewels or the like. For instance, the device might be employed as part of a picture frame, in which case the 105 channel formed above the cross member 22 will receive the edge of the picture, together with the edges of the covering glass and of the back, if any, in a manner that will be obvious without further illustration. 110

When used for holding jewels, the device preferably has the upper portions of the H

formed of single thickness, in order to avoid injury by the file which (as mentioned above) is employed in pressing the upper edges of the device against the stones or like articles. If there were at this upper edge a bend connecting two layers of sheet metal, the file might sever one layer from the other; hence, when the device is used for holding jewels, it is desirable to have a single thickness of material at the upper edges. For other uses, however (say, a picture frame), the upper edges might be formed of double layers, as indicated in Fig. 3, where all the portions of the device have double layers, the two edges 23 being located at any suitable point, say at the transverse member of the H.

Furthermore, it is not essential that the upright members be perpendicular to the transverse connecting member, but in some cases I might adopt an arrangement such as shown in Fig. 4, where the side members 20' and return members 21' are disposed obliquely to the connecting member 22', and converge downwardly, the construction being otherwise the same as described with reference to Figs. 1 and 2.

In the jewelry setting box or holder illustrated by Figs. 5 and 6, the box or holder proper, of H-shaped cross section, is of the same character as in Figs. 1 and 2, but the transverse connecting member 22, instead of being solid as before, is provided with perforations 24 to receive pins 25 secured in place by soldering or otherwise. These pins, besides serving an ornamental purpose, hold the stones A of the character shown in Figs. 5 and 6 or like articles in position more firmly than this can be done by the members 20 alone, and are applicable especially when the stone has cut-away corners, as shown in Fig. 5. These pins 25 also produce compartments or fields of square or other shape in the jewelry setting box and thus guide the workman in properly placing the stones or other articles. These stones may rest on the imperforate portion of the connecting member or bottom 22, or in some cases said member may have additional openings 26 in which the stones may be seated, or through which they may even project downwardly.

In Figs. 7 to 13 I have illustrated three forms of my invention which are intended particularly for bracelets, chains, or other articles made up of links to give them flexibility.

According to Figs. 7, 8, and 9, the box member or holder is of about the same construction as in Figs. 1 and 2, with the following differences: The vertical side members 20" extend the full length of the body and of the cross member 22" only below said cross member, the upper portions of said side members being shortened at one end of the body member or link, as shown

best in Fig. 8; the return members 21" extend the full length of the body. At one end of the cross member 22" (the one where the side members 20" are shortened), I have shown two openings 22a for the reception of wire links 27 which serve to connect this body with a similar end of a neighboring body or box member of the chain, bracelet, or other article. At the other end of the body shown complete in Figs. 7, 8, and 9, I have shown a cross pin or rivet 28 located under the connecting member 22" and secured to the return members 21" and to the lower portions of the side members 20". On this cross pin I have shown pivotally mounted a sheet metal link 29, of a width slightly less than the distance between the two return members 21". This link 29 connects the body member shown complete in Figs. 7 and 8, with a similar end of a neighboring body member, as indicated at the right in said figures.

In Figs. 10 and 11, the side walls 20" and return walls 21" are of the same construction as in Figs. 7, 8, and 9. At the end where the end walls are shortened, I have shown the connecting member 22b provided with a transverse opening or slot 22c, serving to receive a sheet metal link 29' similar to the link 29 described above, to connect this body with a like end of a neighboring body. At the other end of the body, I have shown the connecting member 22b bent up, as at 22d, to form a transverse end wall between the upper portions of the walls 20". At the same end, I have shown a cross pin or rivet 28' for connection with a sheet metal link 29" of the character referred to above. In the particular arrangement shown, the pin lies beyond the upturned portion 22d, and is therefore not covered by the connecting member 22b; but this arrangement of the pin 28' is not essential.

In Figs. 12 and 13, the left-hand portion is of the same construction as in Figs. 10 and 11. At the right-hand end, however, the connecting member 22e extends the full length of the body, and the upper portions of the side walls 20e are bent transversely over said member 22e to close the space at this end. Below said connecting member, I have shown a cross pin or rivet 28" to connect with a sheet metal link 29a of the same character as referred to above; this link is somewhat longer than the links 29, 29', and 29".

It will be understood that the box-like space formed between the upper portions of the side walls is adapted to receive jewels or other ornamental articles; this space may be open at the ends of the body, as in Figs. 1 to 9, or transverse walls may be provided at one end of each body, as in Figs. 10 to 13, and obviously, both ends of the body might be constructed alike, so as to

close said space at each end. The wire or sheet metal links connecting adjacent bodies may be connected either directly with the connecting member 22 etc., as in Figs. 7, 5 8, and 10 to 13 at the left-hand end of each body, or with a cross pin of the character shown in said views at the right-hand end.

As has been mentioned hereinabove, my invention, while designed particularly for 10 use as a jewel holder or so-called jewelry setting box, may be employed for other purposes, say as a member for a picture-frame. Being made of sheet-metal, this article can be manufactured readily without the use of 15 expensive apparatus.

In connection with Figs. 5 and 6, I have stated that the connecting member 22 may have openings 26. These not only serve to 20 position the stones, but also reduce the amount of metal required, which is an important consideration when the article is made of expensive material, say platinum. While I have shown the longitudinal upright walls and the transverse walls 25 imperforate, it will be obvious that they might be perforated for ornamental purposes, or simply in order to save metal.

I claim as my invention:

1. A jewelry setting comprising a body 30 having a connecting member, return members extending downwardly from the longitudinal edges of said connecting member, and side members located exteriorly of said return members and extending upwardly 35 from the lower ends of said return members to above the level of said connecting member, in combination with a jewel held in the space between said connecting member and the portions of the side members above 40 the connecting member.

2. A setting comprising a body having a connecting member, return members extending downwardly from the longitudinal edges of said connecting member, and side 45 members located exteriorly of said return members and extending upwardly from the lower ends of said return members to above

the level of said connecting members, in combination with an article held in the space between said connecting member and 50 the portions of the side members above the connecting member, said article projecting above the upper edges of said side members.

3. A jewelry setting comprising a body 55 having a connecting member, return members extending downwardly from the longitudinal edges of said connecting member, side members located exteriorly of said return members and extending upwardly 60 from the lower edges of said return members to above the level of said connecting member, and means for connecting the ends of said body loosely with adjoining bodies of the same character. 65

4. A jewelry setting comprising a body having a connecting member, return members extending downwardly from the longitudinal edges of said connecting member, side members located exteriorly of said return members and extending upwardly 70 from the lower edges of said return members to above the level of said connecting member, and means for connecting the ends of said body loosely with similar adjoining 75 bodies, said connecting means being located between the planes containing said side members.

5. A jewelry setting comprising a body having a connecting member, return members 80 extending downwardly from the longitudinal edges of said connecting member, side members located exteriorly of said return members and extending upwardly 85 from the lower edges of said return members to above the level of said connecting member, and means for connecting the ends of said body loosely with similar adjoining bodies, said connecting means extending through the connecting members of the 90 respective bodies.

In testimony whereof I have signed this specification.

JOSEF PEJCHAR.
